PORTABLE DRIVING DEVICE

Karl Matts Vigborg, Stockholm, Sweden, assignor
to Kooperativa Förbundet Förening U. P. A.,
Stockholm, Sweden

Application December 8, 1939, Serial No. 308,210
In Sweden December 22, 1938

3 Claims. (Cl. 64—4)

Previously are known household apparatus provided with electrical motors for facilitating their handling. Thus, each apparatus of this kind has been equipped with a special motor necessarily dimensioned according to the work to be performed by the apparatus. However, since an electrical motor often costs considerably more than the household apparatus to be driven by the same, the commendable endeavours to motorize the operation of household apparatus cannot lead to any great and desired success in this way. Even if the costs of running thus do not impede such a mechanical operation, the high buying-prices make a solution of said problem in the earlier manner difficult or, for 15 the most, impossible.

The present invention, however, which relates to a portable device for driving household apparatus, tools and the like, solves the problem in a very simple manner. The device, which consists of an electrical motor enclosed in a casing, is substantially characterized in that the casing has the shape of a rectangular parallelepiped so as to form a support for the device and contains at least two not coaxial shafts, located entirely within the casing and driven under different gear ratios, as well as a fastening means adapted to fix a household apparatus, a tool or the like to the outside of the casing in such manner that the drive shaft of the apparatus will be in driving engagement with one of the shafts of the device. Since the device according to the invention has at least two shafts driven under different gear ratios, it is thus possible to drive all hitherto common household apparatus and the most common tools of a household.

One embodiment of the invention is illustrated on the accompanying drawing, in which

Figures 1 and 2 show the device when seen from two sides perpendicular to each other, Figure 2 being partly a sectional view.

On the drawing reference numeral 1 indicates an electrical motor enclosed in a casing 2. 3 is the contact for connecting an electrical conduit and 4 a switch of suitable construction. In addition to these known devices there should also be provided safety means not particularly shown on the drawing and also a radio disturbance protection. The casing may also be provided with a handle 5 indicated by dot-dashed lines in Figures 1 and 2. The shaft 6 of the electrical motor 1 via a worm gear 7 is in driving engagement with a sleeve-shaped shaft 8 mounted in the casing 2. The toothed wheel fixed to the shaft 8 and forming part of the worm gear is also in driving mesh

5 with a greater toothed wheel 11 fixed to a sleeve-shaped shaft 10. Thus, the shafts 8 and 10, rotating in opposite directions, will be driven under various gear ratios. Each of the shafts 8, 10 has a diametrically running pin 12 intended to serve as drive member for the drive shaft of the household apparatus to be brought into driving engagement with one of said shafts. The free end of the shaft of the household apparatus, therefore, is preferably given the shape shown in Figure 2, in which reference numeral 13 indicates a spice- or almond-mill, the drive shaft 14 of which has a fork-shaped end portion. By forming the connections of the various shafts in the manner described above and shown on the drawing it is also possible to connect the different shafts even during the rotation of the shafts 8 and 10.

In order that a household apparatus may be 20 fastened to the outside of the casing 2 a plate 15 having a number of teeth 16 is displaceably provided within the casing. The plate 15 is guided by means of a pin 9 engaging a guide slot in the disc, and by means of a bow-shaped portion 17 fixed to the inner side of the casing. The teeth 16 engage the threads of a screw 18. This screw, the fluted head 19 of which is accessible from outside, is mounted with its free end in the bow-shaped portion 17. By turning said screw it is thus possible to reciprocate the plate 15. The latter is so shaped that its edge portions 20 may be brought to cover a greater or smaller part of holes 21 made in the casing. Pins 22 fixed to the 25 respective household apparatus (Figure 2) and corresponding to the holes 21 are adapted to be inserted into the same, and the edge portions 20 of the plate 15 are adapted to engage grooves or recesses in the pins 22 when the plate assumes the position shown in Figures 1 and 2. If the 30 household apparatus intended to be connected to the shafts 8 and 10 are provided with pins 22 and with a drive shaft formed as above described, the respective household apparatus may thus be 35 put into driving engagement either with the shaft 8 or with the shaft 10, in accordance with the motive power and the direction of rotation which 40 may be suitable for the drive shafts of the various household apparatus.

Having now described my invention, what I 45 claim as new and desire to secure by Letters Patent is:

1. The combination of a driving device and an exchangeable rotary driven appliance, said driving device comprising a casing, an electrical motor in said casing and means located on the 55

motor shaft for coupling the latter to the shaft of the exchangeable rotary driven appliance, said appliance having a plurality of pins secured thereto, said pins being adapted to project into corresponding holes of said casing, and a single slidable locking means located in said casing and being capable of engaging said pins of said appliance.

2. A combination as claimed in claim 1, in which said pins have transverse slots and said 10

slidable locking means is a plate having edge portions capable of engaging said grooves.

3. A combination as claimed in claim 1, in which screw threads are provided on said locking means and a screw projecting from the outer casing surface inwardly, said screw engaging said screw threads so as to raise and lower said slid-able locking means upon rotation of said screw.

KARL MATTS VIGBORG.
